UNITED STATES PATENT OFFICE.

REGINALD CHURCHILL, OF BURTON-ON-TRENT, ENGLAND.

VENETIAN BLIND.

SPECIFICATION forming part of Letters Patent No. 595,146, dated December 7, 1897.

Application filed December 23, 1896. Serial No. 616,766. (No model.) Patented in England June 22, 1896, No. 13,771.

To all whom it may concern:

Be it known that I, REGINALD CHURCHILL, a subject of the Queen of Great Britain, residing at Burton-on-Trent, in the county of 5 Stafford and Kingdom of England, have invented certain new and useful Improvements in Venetian Blinds or Collapsible Shutters, of which the following is a specification, and for which I have obtained Letters Patent in 10 Great Britain, No. 13,771, dated June 22, 1896.

This invention pertains to improvements in collapsible blinds and shutters for windows and other analogous uses, and has distinct reference to that class of blind or shutter 15 well known as the "Venetian."

The object of the invention is to construct a collapsible blind or shutter in such a manner that its durability shall be considerably increased, its appearance made neater, and 20 the repairing of the same, when required, facilitated, and this is accomplished by mounting or suspending the slats or laths of which the blind is composed upon a series of inwardly-folding hinge-plates, preferably made 25 of sheet metal or other suitable rigid material, and each hinge-plate being provided with a cut-away portion to provide a central opening when the said hinges are folded, through 30 which the slat-operating cords may pass, as will hereinafter appear.

To these ends the invention consists in the novel features of construction and arrangement of parts hereinafter described, and more definitely pointed out in the claim which concludes this specification.

The invention is illustrated in the accompanying drawings, in which—

Figure 1 is a front elevation of a Venetian blind constructed in accordance with my invention. Fig. 2 is a detail perspective view of a portion of a blind with my improved hinge-plates applied thereto. Fig. 3 is a vertical section of a portion of a blind, showing the hinge-plates and slats opened out. Fig. 4 is a similar view showing the plates folded and slats collapsed. Fig. 5 is an enlarged detail front view of one of the hinge-plates. Fig. 6 illustrates a side and bottom view, respectively, of one of the slat-carriers. Fig. 7 45 illustrates in plan and side elevation, respectively, one of the hinge-plates. Fig. 8 is a modified form of hinge-plate with ornamental 50

stamping. Fig. 9 is a detail sectional view of the stop-knuckle joint of the hinge-plates, and Fig. 10 is a detail view of one of the removable pins which connect the parts of the hinge-plates.

The blind *a* is composed of slats or laths *s*, carried by cross-bars *b* of a depth sufficient to accommodate them, the ends of which 60 cross-bars are fashioned into barrel parts *b*², as clearly shown in Fig. 6. Each and every slat or lath of which the blind or shutter is composed is fixedly connected to two of these cross-bars or carriers *b*, one of the latter upon 65 each end of the lath, and the said carriers are supported or suspended by pairs of inwardly-folding plates *a*², hingedly connected to each other and to the carriers or cross-bars in vertical line on both edges of the slats by 70 knuckle-joints *a*⁵ and hinge-like parts *a*⁶. A pair of these folding plates *a*² are arranged to span the divisional space between each and every slat or lath, and each of the pair consists of two thin metallic parts *a*³ *a*⁴, connected together and also to one of the ends 75 *b*² of the carriers *b* by the simple hinge connections *a*⁵ *a*⁶, a stop being arranged upon the knuckle-hinged part *a*⁵, as clearly shown in Fig. 9, to prevent the possibility of the 80 hinged-together folding fittings straightening out to a vertical line, which would interfere with their action.

One of each of the parts *a*³ and *a*⁴ is clearly shown in front and edge view in Fig. 7, and 85 these and also the carriers to which they are connected are made from thin metal, xylonite, vulcanite, or other such hard-wearing material, and loosely jointed the one to the other, so as to combine and constitute a folding fitting to the slats.

The parts constituting the fitting, when made from sheet metal, are produced by stamping and of certain standard sizes, so as to facilitate duplication should any part become broken or badly worn, and the fitting together of the same is such that they can be very simply disconnected or taken apart and again put together when the blind or shutter is required to be cleaned, and to accomplish 90 this the center pin *a*⁷ of the knuckle and hinged joints is preferably made of wire with one end split to slightly open out and prevent its withdrawal, as shown in detail in Fig. 10.

The knuckle-hinged part a^5 would be made as small as possible consistent with strength, so as to fold close and allow the slats of which the blind is composed to occupy as small a space as possible when the blind is pulled up.

5 The series of slats and their suspending and supporting fittings are carried by a top frame-bar g , (shown in Fig. 1,) of the ordinary construction, and cords f are provided for their 10 pulling up and down and angular movements.

The hinged connection of the fittings to each other can be accomplished in various ways, so long as a free and loose connection is effected.

15 My improved fittings may be suitably embellished and embossed to give an ornamental appearance to the blind, and the wear of the same would be practically indefinite.

Having fully described my invention, what 20 I claim, and desire to secure by Letters Patent, is—

In a Venetian blind or shutter, the combi-

nation with the slats or laths thereof each having cord-openings therein near their opposite ends; of a hanger for said slats comprising a series of inwardly-folding hinge-plates a^3 , a^4 , connected to the opposite sides of the slats by removable pins, each of said hinge-plates being provided with a cut-away portion to provide a central opening, which 25 openings register with the cord-openings in the slats when the hinge-plates are folded, and stop-knuckles on the hinge-joints between the slats to normally hold them out of a vertical line to facilitate the folding operation, substantially as described.

In witness whereof I have signed my name to this specification in the presence of two subscribing witnesses.

REGINALD CHURCHILL.
